UNITED STATES PATENT OFFICE.

HORACE C. WILCOX, OF WEST MERIDEN, CONNECTICUT, ASSIGNOR TO
MERIDEN BRITANNIA COMPANY, OF SAME PLACE.

DESIGN FOR INKSTAND-COVER.

Specification forming part of Design No. 7,871, dated November 17, 1874; application filed October 15, 1874.
[Term of Patent 7 years.]

To all whom it may concern:

Be it known that I, HORACE C. WILCOX, of West Meriden, in the county of New Haven and State of Connecticut, have invented a new Design for Inkstand-Cover; and I do hereby declare the following, when taken in connection with the accompanying drawings and the letters of reference marked thereon, to be a full, clear, and exact description of the same, and which said drawings constitute part of this specification, and represent, in—

Figure 1, front view, and in Fig. 2, side view.

This invention relates to a design for the cover or stopper of inkstands; and consists in the configuration of the article, as shown in the accompanying illustration, and as more fully hereinafter described.

A represents an inkstand, which may be of any desired form. B is the base of the stopper, formed to set onto and cover the open-

ing in the inkstand. Upon the base is a pan, C, the edge of which is made irregular by scallops or points a , more or less in number. The pan is substantially circular, and these irregularities or the depressions afford a convenient support for pen-holders, &c. Upon opposite sides of the pan is an upright, D, supporting an egg-shape ornament, E, which is preferably made to open, as denoted in broken lines, Fig. 2, as a convenient receptacle for stamps, wafers, &c.

I claim—

The design for inkstand-stopper, consisting of the base B, the irregular-edged pan C, support D, and central ornament E, shown in the accompanying illustration, and as herein described.

HORACE C. WILCOX.
